UNITED STATES PATENT OFFICE.

GEORGE I. THEILE, OF HAMILTON, OHIO, ASSIGNOR TO THE HOOVEN, OWENS,
RENTSCHLER COMPANY, OF HAMILTON, OHIO, A CORPORATION OF OHIO.

SUGAR-MILL MACHINERY.

Application filed October 2, 1925. Serial No. 60,136.

This invention relates to the manufacture of sugar, and has to do particularly with the straining of the juice which is expressed from sugar cane and subsequently treated 5 to remove the sugar therefrom.

One of the principal objects of the invention is to provide an improved form of strainer mechanism for use with juice expressing apparatus, which is simple in construction and effective in operation.

Another object of the invention is to provide apparatus of this character which will give clearer juice, and drier trash or screenings than may be secured through the use 15 of apparatus of the character heretofore known.

Other objects and advantages of the invention will be apparent from the description thereof set out below when taken in 20 connection with the accompanying drawing.

In the drawing in which like characters of reference designate like parts throughout the several views thereof,

Fig. 1 is a fragmentary plan view of a 25 sugar mill embodying the form of juice straining mechanism constructed in accordance with this invention;

Fig. 2 is a fragmentary side elevation of the apparatus shown in Fig. 1;

Fig. 3 is a vertical sectional view through the apparatus along the line 3—3 of Fig. 1; and

Fig. 4 is a diagrammatic side elevation of a complete mill constructed in accordance 35 with the invention.

As is well known the greater part of the world's supply of sugar is extracted from sugar cane. In the extraction of the juice in such manufacture of sugar the cane is passed 40 through a succession of sets of heavy crushing or expressing rolls, under high pressure, which squeezes the juice out of the stalks of cane. The resulting squeezed cane, which is called bagasse, is passed successively 45 through succeeding sets or stands of rolls, the expressed juice, with entrained bagasse and the like, running down from the rolls and being collected for subsequent treatment.

Ordinarily the cane is passed first through 50 one or more sets of toothed or grooved rolls called "crushers" which serve to break up the fibers of the cane so as to open the juice containing cells, at the same time squeezing considerable of the juice from the cane. The 55 crushed cane is then passed through what

are known as "mill rolls" which are either smooth surfaced, or provided with circumferential or other grooves, where the remaining juice is expressed from it. Naturally some of the crushed cane, dirt or the like 60 which may be on the cane, and other extraneous materials travel, in greater or less quantity, with the juice and must be removed before the juice can be refined to 65 form sugar.

The first step in the treatment of the juice after it is expressed, therefore, is to strain it so as to remove the greater part of those solid impurities which may be present, —such as cane fiber, and the like. It has 70 been the practice heretofore to provide sugar mills, of the kind generally described above, with collecting troughs associated with the several juice extracting rolls for receiving the juice, and its impurities, from these rolls 75 and to feed the juice onto a strainer which runs alongside the length of the entire mill. Underneath this screen or strainer is a trough which collects the strained juice and 80 from which it is drawn off for further treatment. Traveling over the top of this strainer or screen is some conveyor or other means which causes the screenings to travel along the screen surface. In this conventional construction all of the juice from all of the rolls is delivered onto the same strainer, but at 85 different points thereof, and all of the screenings are caused to travel along the surface of this strainer in the same direction, being thus subjected to recurrent soaking 90 with juice while doing so.

In the form of apparatus shown in the accompanying drawing the defects inherent in the forms of straining apparatus heretofore used are avoided. As shown in the 95 drawing the numeral 10 designates the crusher, or the first set of toothed rolls which act to break up the cane and open the juice containing cells, and the numeral 11 the first set of mill rolls. Juice from this 100 crusher and from the first mill flows into a juice collecting pan 12 common to the crusher and first mill. From this pan the juice flows through a delivery spout 13 to a juice strainer or screen 20 arranged alongside the end of the rolls of the third mill and lengthwise of the sugar mill as a whole. This juice strainer is arranged at substantially right angles to the axes of the rolls. The second mill 15 has a juice collecting pan 110

16 associated therewith, also having an outlet or delivery pipe 17 through which the juice flows to the juice strainer 20. As shown this pipe 17 leads into the spout 13 5 and they thus empty in common onto the screen of this juice strainer. The screen or strainer 20 overlies a juice pan 21. As the juice flows onto this screen it passes therethrough into the pan 21 beneath the screen 10 and the trash and other extraneous material remains on the screen. This screen may be of any conventional structure as the particular character and the material forming the screen as well as the openings of the 15 screen need not vary from the heretofore conventional practice. And the pan beneath the screen receiving the juice may be of any desired character. Very satisfactory operation has been secured where these pans 20 are made of sheet metal, and supported in any suitable way upon the mill foundation, or from the mill structure. This juice strainer is arranged parallel to the sugar mill as a whole, and to one side thereof.

25 Cooperating with the screen 20 is a flight conveyor designated generally by the numeral 25. This conveyor may be of any suitable conventional character and is shown as comprising a series of wooden 30 slats 26 mounted within spaced endless chains 27, or the like, which are driven by a pulley or sprocket wheel 28 from a motor 29, or any other suitable power sources. The strainer 20 is of only such length that 35 sufficient screen surface will be provided for securing effective straining of the juice from the trash. As shown, this strainer lies alongside the third mill, and the screen 20 at one end extends downwardly in a lip or 40 chute 30, through which the screenings upon the screen are fed into a horizontal conveyor trough 35 located beneath the strainer 20.

The juice from the third mill 40 and 45 fourth mill 41 is collected in the same way as already described, in the collecting pans 42 and 43 respectively, from which it is fed through delivery pipes 44 and 45 to the juice strainer 50 which is similar in construction to the strainer 20 described above. 50 Associated with this juice strainer 50 is a drag or slide conveyor of the kind described above, and operated in a similar manner. This conveyor is adapted to move the screenings in the direction of the arrow 53, 55 and to feed them through the chute 54, preferably arranged at that end which is adjacent to chute 30 of the strainer 20, into the horizontal conveyor trough 35. This arrangement need not necessarily be followed as the parts can be arranged in any other suitable manner. This horizontal conveyor is provided with a flight conveyor 55, operated by a motor 56 or in any other suitable manner, and is adapted to move the material thereon in the direction of the ar-

row 57. At the end toward which the screenings are fed the trough 35 is provided with a chute 58 which overlies the upwardly inclined conveyor trough 60. This conveyor trough also has a flight conveyor 61, of the character described above, independently operated by a motor 62 or the like which in turn moves the material received in the trough upwardly and into the trough 63 which has a scroll conveyor 64 therein, which is operated also by the motor 62 together with the flight conveyor 61. Adjacent its free end the scroll conveyor trough 63 is provided with an opening 65 through which the screenings are fed back into the carrier connecting the first and second mills so that it passes with the bagasse stream through the remaining mills.

Any desired number of mills may be used, some installations having as high as six or seven stands of mills, as shown diagrammatically in the drawing. Also the juice from each mill may be screened separately or the juice from several mills may be combined as desired and to suit requirements, and the arrangement shown need not be adhered to.

As shown diagrammatically the fifth and sixth mills, 70 and 71, are provided with a common juice strainer 72 and with collecting pans and delivery pipes for feeding the juice to the strainer as described above. There is also a flight conveyor designated generally 75 for feeding the screenings into the conveyor trough 35, the flight conveyor in this case being also independently driven by its own motor as described above. The seventh mill 80 has a collecting pan and delivery spout which feeds the juice onto the strainer 81, which also has a flight conveyor 82 for feeding the screenings into the conveyor trough 35. Each juice strainer operates independently of the others and feeds all the screenings into the common conveyor trough 35 whence they are returned to the bagasse stream.

The apparatus thus described is very much superior to the conventional juice strainers as heretofore used. In the conventional type of strainer, which comprises one big strainer arranged parallel to the length of the mill or alongside the several sets of rolls, there is a separate juice delivery pipe, or inlet, to the one big strainer from each mill or combination of mills. The material delivered onto this one big strainer at the crusher end is dragged over the surface of the screen, the juice straining off as this is done. As this screened material moves along the screen it passes successively under the spout or juice delivery pipe leading from each succeeding juice collecting pan and is re-saturated with juice by the fresh juice and

material delivered onto the screen at that point. The material on the screen is therefore soaked afresh with juice at each such point. But with the form of device described, where separate screens are provided for each mill or for certain sets of mills, and the separate screens are arranged independently alongside the mills, the juice is strained from the trash independently by each strainer and this dried trash is independently delivered into the conveyor through 33. Consequently this screened trash does not again come in contact with the juice. This will, therefore, give clearer juice and drier trash. Furthermore, because of the arrangement shown, the size of each strainer unit may be independently adjusted to suit the volume of material delivered to it by the mills which it serves, and each conveyor may be independently adjusted to accord with the quantity of screenings which it must handle. Or, any juice strainer, or conveyor, may be cut out of operation without affecting the operation of any other. Also the screening surface being shorter is more easily kept clean, more readily replaced, and less likely to wear rapidly.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. Apparatus for extracting juice from sugar cane and the like, comprising a plurality of sets of rolls, a plurality of juice strainers arranged alongside the ends of said sets of rolls, means for feeding to each of said strainers juice from certain of said sets of rolls, each strainer acting independently to strain the juice fed thereto, means associated with each strainer for removing the screenings therefrom, and a common conveyor means for receiving the screenings removed from the several strainers to return said screenings to the bagasse passing through the rolls.

2. Apparatus for extracting juice from sugar cane and the like, comprising a plurality of sets of rolls, a plurality of spaced juice strainers arranged alongside the ends of said rolls, means for feeding to each juice strainer the juice from certain of the said sets of rolls, independently operating means for removing the screenings from

each of the said juice strainers, a common conveyor associated with the several juice strainers to receive the screenings removed from the said juice strainer, and a second conveyor cooperating with the common conveyor to receive the screenings and return them to the bagasse passing through the rolls, said second conveyor comprising a horizontal portion arranged above the bagasse stream and an inclined portion leading up to said horizontal portion.

3. In apparatus for extracting juice from sugar cane and the like, comprising a plurality of sets of rolls through which the cane is passed to express the juice therefrom, means for straining the expressed juice comprising a plurality of sets of strainers arranged alongside the ends of the rolls, means for feeding to each strainer the juice from certain of the said rolls, each strainer acting to independently strain the juice fed thereto, the said strainers being arranged generally alongside the apparatus in alignment and with the adjacent ends spaced apart, a chute arranged between each two adjacent ends, means associated with each strainer for moving the screenings along said strainer toward one end thereof to pass through the chute arranged at such end, a common conveyor positioned beneath the said chutes to receive the screenings passing therethrough, and a second conveyor associated with the common conveyor to receive the said screenings and return them to the bagasse to again pass through the rolls.

4. Apparatus of the character described, comprising crushing rolls, a screen arranged alongside the ends of said crushing rolls, collecting means associated with said rolls and said screen, means for feeding onto the screen the material collected from the rolls, a conveyor associated with said screen for removing the screenings therefrom, and means for returning the removed screenings to again pass through the rolls.

5. Apparatus for extracting juice from sugar cane and the like, comprising a plurality of sets of rolls, a plurality of independent juice strainers arranged alongside said rolls and parallel with the path of travel of the cane, and means for feeding to said juice strainers the juice after its separation from the bagasse from certain of said sets of rolls, to independently strain the juice from the said several sets of rolls.

In testimony whereof I hereto affix my signature.

GEORGE I. THEILE.
